(57) **CLAIM**

The ornamental design for a pedestal for holding a rangefinder laser as shown and described.

DESCRIPTION

FIG. 1 is a front elevational view of a pedestal for holding a rangefinder laser showing our new design;

FIG. 2 is a back elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The broken lines in the drawings illustrate portions of the pedestal for holding a rangefinder laser that form no part of the claimed design. The broken lines of FIG. 2 shown in white for clarity of illustration form not part of the claimed design.
